CONVERSION OF HYDROCARBON GASES

Jesse A. Guyer, Bartlesville, Okla., assignor to
Phillips Petroleum Company, a corporation of
Delaware

Application August 27, 1934, Serial No. 741,693

4 Claims. (Cl. 196—10)

This invention relates to the conversion of hydrocarbon gases into normally liquid hydrocarbons boiling in the motor fuel range.

There are produced in the cracking and distilling of oil, large quantities of hydrocarbon gas containing both paraffin and olefin hydrocarbons and suitable for conversion into gasoline. From natural gas there are extracted gaseous paraffin hydrocarbons, propane and butane, 10 which likewise can be converted into gasoline.

Various processes for the conversion of normally gaseous hydrocarbons into gasoline have been proposed. Gaseous olefins under heat and pressure may be polymerized to gasoline. Gaseous paraffin hydrocarbons, particularly propane and butane, may be converted into gasoline by heating under a high pressure to a cracking temperature ordinarily higher than that required for polymerizing olefins, whereupon simpler olefins 15 are formed by dissociation and normally liquid hydrocarbons then result from the polymerization reactions which ensue.

All the gaseous olefins, namely ethylene, propylene and the butylenes, can be readily converted into polymers by heating under high pressure. Since the polymerizing tendency is nearly the same for them all, all these olefins will enter into reaction when a mixture is subjected to polymerizing conditions of heat and pressure, 20 though paraffin hydrocarbons require temperatures so much higher than the olefins that a separate conversion step is desirable for olefin-rich and paraffin-rich gases respectively. A mixture of the gaseous paraffins, unlike the olefins, cannot be converted efficiently into gasoline hydrocarbons unless certain restrictions are placed on the composition of the mixture. The cracking velocity of the gaseous paraffins decreases rapidly with decrease in molecular weight. Methane 25 is, of course, virtually inert and is accordingly undesirable. I have discovered that butane gives the highest yield of gasoline and is accordingly the most valuable of the gaseous paraffins, but ethane and even propane, by reason of their more refractory character when accompanying butane 30 are only slightly cracked at the moderate temperatures required for cracking butane. Moreover, these temperatures cannot be exceeded if the formation of coke is to be avoided. Ethane 35 and propane may be present in no more than a very small proportion if a reduced efficiency of the cracking step is to be avoided. I have found that very little ethylene is produced in the cracking of butane under high pressure but that a 40 substantial proportion of propylene is formed

which may to advantage be separated from the reaction products and returned to the cracking operation. Small proportions of olefins, preferably under 20%, may to advantage accompany butane, and in such a case will augment the 5 gasoline yield without necessitating any great reduction in the extent of conversion of the butane.

My invention provides a more economical means for producing gasoline from two gases, 10 one predominantly paraffinic, and one containing a considerable quantity of olefins. The invention provides for subjecting a mixture of gaseous hydrocarbons containing a substantial proportion of olefins to heat and pressure to 15 effect polymerization of the olefins into gasoline, then subjecting the surviving olefin-depleted gases to fractional distillation to effect the removal from the mixture of specifically the methane and non-hydrocarbon gases, the ethane 20 and the small proportion of ethylene accompanying it, and at least a substantial part of the propane. The remaining gaseous hydrocarbons are mostly paraffinic and comprise butanes for 25 the most part, a small amount of butylenes and preferably propylene and are subjected in a second conversion step to a cracking temperature at a high pressure to effect conversion into gasoline.

A hydrocarbon mixture of this latter composition is peculiarly suitable for the reasons set forth for conversion under the rather drastic conditions of temperature and pressure required by paraffins, where a high conversion into gasoline is to be effected in the heating operation. 35 The invention provides for effecting by a single fractionating system the treatment of effluents from both high pressure conversion operations to produce a paraffinic charging stock meeting the strict requirements for efficient conversion. 40

Gases suitable for treating in the olefin polymerization step in my process will contain 25% or more of olefins and may contain as high as 60% of olefins. Gases from cracking stills are suitable but gaseous concentrates obtained from 45 still gases by compression or absorption means and containing a lower proportion of methane are preferable. The olefin-rich gases may be subjected to pressures of 500 to 1000 or 3000 pounds per square inch or more and temperatures of 700° F. to 1000° F. to effect conversion and the paraffin-rich gases may be subjected to pressures of 1000 to 3000 pounds or more per square inch and 950 to 1100° F. to effect conversion but in most cases a pressure of 3000 pounds per square inch 55

and about 890° and 1020° F. respectively for the two operations give best results, the reaction time being on the order of two or three minutes in each case.

5 The advantages of my process will be apparent from the following description, taken in conjunction with the attached drawing, in which 1 is a pipe conveying olefin containing gases through the heat exchanger 2 and the furnace 3 to the exothermic reactor 4. In this furnace and reactor they will be maintained at pressures on the order of 2500 pounds per square inch, and at a temperature on the order of 890° F. From the reactor, the gases and polymers will pass back 10 through the heat exchanger 2, which may be omitted if more heat is desired for the conduct of the subsequent fractionating steps, and through the transfer line 5 into the fractionating column 6 operated at suitable superatmospheric pressure 15 but below 500 pounds per square inch. Paraffinic hydrocarbons of an average molecular weight of from 45 to 70, and which will usually predominate in butanes will be fed through the pipe 7 to the furnace 8 under pressures on the order of 2500 pounds per square inch, and cracked at 20 temperatures on the order of 1020° F. From this furnace they may be passed through the scrubber 9, into which a cooling oil may be injected if desired, and through the heat exchanger 10, which 25 may be omitted, into the line 17 and the fractionator 6 substantially as shown. From the fractionator, gasoline and tar are removed as a kettle product, and the tar separated, if desired, in the fractionator 12. The overhead product, principally butane and lighter hydrocarbons, is withdrawn 30 through the line 13 to the fractionator 14, from which a kettle product consisting predominantly of butane is withdrawn through line 15 for recycling in the high temperature cracking coil. Light gases are discarded through the line 19. A side stream predominating in propane and propylene may be withdrawn from the fractionator 14, and injected into the side of the fractionator 16 in which it is separated by highly 35 efficient fractionation into a propylene and lighter fraction, and a propane fraction, which is discarded. The propylene and lighter fraction may be recycled to either the polymerizing step or the cracking step as desired.

50 Oil not vaporized in the scrubber 9 may be passed around the fractionator 6 through the line 18 to the fractionator 12 if desired.

The fractionating columns will, of course, be 55 equipped with suitable refluxing and reboiling equipment, liquid level controls, and the like, here omitted for the sake of simplicity. Also, pressure reduction valves, pumps, and the like will be used wherever necessary.

60 Many other slight modifications of my process will be apparent. For example, I may pass recycle stock from the line 15 through the heat exchanger 10 and the line 20 to the furnace 8, introducing it into the reaction coil at an intermediate point 65 if desired. I may also enclose both heating coils in the same furnace setting, regulating the supply of heat to each coil by means of dampers or equivalent means.

65 It is evident that my process will be operative 70 on a wide variety of charging stocks. However, I prefer to charge to my high temperature cracking coil a material containing substantial quantities of butanes, and to my polymerizing furnace any volatile hydrocarbon material containing 75 substantial quantities of olefins.

A wide range of operating pressures may be used in the fractionating columns shown as 6 and 14 in the accompanying drawing. In general, it will be found advantageous to operate the column 6 at pressures less than 500 pounds per 5 square inch, and pressures on the order of 50 to 250 pounds per square inch will be found most suitable. When operating the column 6 at the lower pressures, it will generally be found advantageous to insert a pump or compressor in the 10 line 13, increasing the pressure in the column 14 to 200 pounds per square inch or more. However, if refrigeration is available for cooling the reflux in the column 14, considerably lower pressures may be used. The column 12 will normally be 15 operated at pressures on the order of one or two atmospheres.

Having described my process, what I claim is:

1. The process of converting normally gaseous hydrocarbons to normally liquid hydrocarbons, 20 which comprises subjecting olefin bearing gases to polymerization conditions of time and temperature at pressures in excess of 500 pounds per square inch while simultaneously subjecting predominantly paraffinic hydrocarbons of an average 25 molecular weight between 45 and 70 to pyrolysis conditions at pressures in excess of 1000 pounds per square inch, passing substantially all the products of the aforesaid polymerization and the 30 major portion of the products of the aforesaid pyrolysis into a separating zone, separating them therein into a fraction consisting predominantly of gasoline and heavier hydrocarbons, and a fraction 35 consisting predominantly of butane and lighter hydrocarbons, withdrawing the first mentioned fraction from the system while passing the aforesaid butane-containing fraction to a second separating zone, separating it therein into a fraction lighter than butane, and a fraction of 40 high butane content, discarding the said lighter fraction, while passing the fraction of high butane content back for pyrolysis in admixture with the aforementioned predominantly paraffinic hydrocarbons.

2. The process for converting normally gaseous hydrocarbons into volatile normally liquid hydrocarbons which comprises heating an olefin-rich gas to a polymerizing temperature in a first heating zone, while maintaining it at a 45 pressure in excess of 500 lbs. per square inch, heating a paraffin-rich gas consisting predominantly of butane to a cracking and polymerizing temperature in a second heating zone while maintaining it at a pressure in excess of 1000 lbs. per square inch, passing substantially all 50 the products from the first heating zone together with the products from the second heating zone into a first separating zone, there separating the products into a gasoline and heavier fraction, and a butane and lighter fraction, passing the butane and lighter fraction to a second separating zone, separating it therein into a light fraction and a fraction consisting predominantly of butanes, discarding the light fraction, and returning the butanes to the second heating zone. 55

3. The process for converting normally gaseous hydrocarbons into volatile normally liquid hydrocarbons which comprises heating an olefin-rich gas to a polymerizing temperature in a first heating zone, while maintaining it at a pressure 60 in excess of 500 lbs. per square inch, heating a paraffin-rich gas consisting predominantly of butane to a cracking and polymerizing temperature in a second heating zone while maintaining it at a pressure in excess of 1000 lbs. per square 65

inch, passing substantially all the products from the first heating zone together with the products from the second heating zone into a first separating zone, there separating the products into 5 a gasoline and heavier fraction, and a butane and lighter fraction, passing the butane and lighter fraction to a second separating zone, separating it therein into a light fraction, a fraction consisting predominantly of butanes, and 10 10 a fraction rich in propylene and propane, passing the last mentioned fraction to a third separating zone, separating it therein into a fraction rich in propylene, and a fraction rich in propane, discarding the fraction rich in propane, and passing the fraction rich in propylene 15 15 and the aforementioned fraction consisting predominantly of butanes back to the second heating zone for retreatment.

4. The process of converting normally gaseous hydrocarbons to normally liquid hydrocarbons, which comprises subjecting olefin bearing

gases to polymerization conditions of time and temperature at pressures in excess of 500 pounds per square inch while simultaneously subjecting predominantly paraffinic hydrocarbons of an average molecular weight between 45 and 70 5 to pyrolysis conditions at pressures in excess of 1,000 pounds per square inch, passing substantially all the products of the aforesaid polymerization and the major portion of the products of the aforesaid pyrolysis into a separating system, 10 separating therefrom a first fraction consisting predominantly of gasoline and heavier hydrocarbons and removing the fraction from the system, separating also a second fraction of high butane content and passing said second 15 fraction back for pyrolysis, separating also a third fraction consisting of hydrocarbons lighter than the second fraction and discharging the last mentioned fraction from the system.
